RADIOTUBE.

Application filed October 15, 1925. Serial No. 62,550.

In radio tubes as in incandescent lamp bulbs, there is always a certain amount of filament stretch or sag which takes place in time during the use of the tube. In tubes which employ filaments of unusual length this tendency is more pronounced and frequently results disastrously by causing a short circuiting of the filament with the grid or other element of the tube, thereby incapacitating the tube through burning out the filament or otherwise.

Also, in radio tubes there is a certain amount of filament electron emission which is lost because of electron projection out of alignment with the grid or plate provided for its reception.

My present invention has for an object to so shape the parts of the usual electron emissive tube that filament sag may take place without damaging the tube or affecting its operation.

A further object is to produce a radio tube in which considerably greater efficiency of operation is obtained with the same electronic action as in other tubes.

These and other objects are attained in the tube described in the following specification and illustrated in the accompanying drawing, in which:

30 Fig. 1 is a sectional elevation of a tube embodying my invention.

Fig. 2 is a sectional elevation of a tube also embodying my invention, but of different form.

35 Fig. 3 is a sectional elevation of a tube embodying my invention, but of a modified construction.

Fig. 4 is a sectional elevation of a tube embodying my invention in a still further modified form.

40 Fig. 5 is an elevational view upon a somewhat reduced scale, of a double ended tube embodying my invention, mounted in a clip or socket which also constitutes a feature of my invention.

Fig. 6 is a plan view of the tube and its mounting as shown in Fig. 5.

Fig. 7 is a perspective view of one of the clip mounting elements shown in the mounting of the tube as disclosed in Fig. 5.

50 I will first describe the form of tube I have shown in Fig. 1. In this tube I have employed a double ended construction in which certain terminals, although applying to but one element of the tube, are brought out at opposite ends of the tube, while the

other tube elements have terminal connections at but one or the other end of the tube. The embodiment of the tube consists of an enclosing envelope 8 of glass which is provided with sealed ends in which are inwardly projecting stems 9 and 10. In these stems are fused the supporting posts of the filament, grid and plate elements.

55 Posts 11 and 12 at opposite ends of the tube are provided for supporting the plates 13 and 14. These plates are of especial shape, being of approximate conical or cup shaped form for purposes which will be hereinafter more fully described. I have shown these plates so positioned that their bases or larger ends lie adjacent to the stems at their respective ends of the tube, although the functioning of the tube will be just as effective should they be placed in reverse 70 positions, in parallel positions, or with both facing in the same direction as shown in Fig. 5.

75 Posts 15 and 16 are also fused into the stems 9 and 10 and support grids 17 and 18 which are within and which lie closely adjacent to the inner walls of the plates, thereby also being of substantially conical shape conforming to that of the plates.

80 There now remains but two terminal posts 19 and 20 to which are connected the opposite ends of the filament. This filament has two effective or electron emissive portions 21 and 22 and a centrally located relatively rigid thickened portion 23 which is located 90 in the brace 24 having its ends fused in the glass stems at the ends of the bases. The effective portions 21 and 22 of the filament are of the usual thoriated or other especially prepared wire which is designed for 95 very active electron activity upon being subjected to a current of sufficient voltage. These filament portions are of novel shape inasmuch as they are wound into spiral shape in general conformance with the shape 100 of the grids and plate. The size of these spiral filament windings is such that they lie closely adjacent to the inside of the grids as do the grids from the plates.

105 The posts in the stems 9 and 10 terminate in the wires 25, 26 and 27 at one end of the tube and in the wires 28, 29 and 30 at the opposite end of the tube. These wires are made available for connection with a circuit in which the tube is to be used, by providing terminals 95, 96 and 97 which are shown in Figs. 5 and 6 as molded into bases

98 of bakelite. Terminals 95 and 97 are made in the form of lugs extending from the ends of the tube, while terminal 96 is made in the form of a plate molded in 5 the side of the base. The terminals 95 and 97 are connected with the grid and plate wires 25 and 27 respectively, while plate 96 is connected with the filament wire 26. At 10 the opposite end of the tube the same relationship holds good also. Of course it is perfectly obvious that the terminals 95 and 97 may be mounted in a metal base provided they are suitably insulated therefrom, the base itself serving as terminal plate 15 96. I find it convenient to provide each of the terminals 95 and 97 with a pin 99 in order that the tube may be easily mounted and a suitable connection established at the same time. This mounting is accomplished 20 by means of a clip of unique construction which I will now describe.

Each end of the tube is mounted in a clip of the same construction. This clip consists of a block of insulating material 100 to 25 which the terminals are attached, a portion 101 of the block being provided for the reception of the bolts 102 by means of which the clip is secured to the panel 103 adapted to support the tube. The terminals consist 30 of a pair of spring fingers 104 and 105 which are attached to the sides of the block and have binding posts 106 and 107 for purposes of circuit connection. Between these fingers is a depending spring finger 108 35 which is also mounted on the block and which has a binding post 109 for purposes of circuit connection. Fingers 104 and 105 are somewhat diverging and have notched ends 110 and 111 in the form of hooks 40 adapted to engage the pins 99 on the tube terminals 95 and 97. The spring-like action of these fingers is such that the tube when placed in position, will have to be pressed into position to overcome the tension of these 45 fingers, thus causing it to snap into position and to be held securely. In this position the fingers 108 will bear yieldingly against the terminal plates 96 at the ends of the tube.

50 The tube shown in Fig. 2 is designed along the same general lines as the tube just described, but contains but one plate and one grid instead of two of each as in the tube shown in Fig. 1. The envelope 41 of 55 this tube is provided with the usual base 42 and locating pin 43, while the contact pins 44, 45, 46 and 47 correspond to the pins of the usual tube. The stem 48 carries the usual posts 49, 50, 51 and 52 which support the 60 plate 53, filament 55 and grid 54 respectively as in other tubes, the posts being connected with the contact pins by the wires shown in dotted lines and which pass through the base. The novel features of the 65 tube consist of course in the shape of the

plate and grid, and particularly in the spiral form of the filament, which shapes have been described in the description of the tube shown in Fig. 1.

In Fig. 3 I have shown a tube built somewhat along the lines of Fig. 1; but disclosing the plate and grid elements 56 and 57 at one end with their larger ends facing the larger ends of the plate and grid elements 58 and 59 of the opposite end of the tube. 70 This condition is just the reverse to the condition shown in Fig. 1, and is done for a purpose which will be described. The filament 60 which occupies the plate and grid elements of this tube is also of the spiral 80 type, but, instead of being of a single conical formation is of a double conical formation adapted to lie closely adjacent to the inner walls of the grids. Posts 61, 62, 63, 64, 65 and 66 support the respective plates, 85 grids and filament 56 to 60 inclusive, while wires 67 to 72 inclusive afford connection of the respective posts and elements with the circuit in which the tube is to be placed.

Fig. 4 is a modified form of the invention 90 herein described, in which it shows a tube of dual functioning, but which is nevertheless of single ended or single base construction. In this tube I employ but a single filament having two electron emissive portions 73 and 74 with an enlarged non-effective portion 75 between them. In this respect the tube is like that shown in Fig. 1, except that the two effective portions are brought parallel to one another to form a 100 U-shaped filament. The central portion 75 of the filament is supported by a lever 76 which is fused into the stem 77 of the base. Surrounding the effective portions 73 and 74 of the filament are the respective grids 105 78 and 79, while surrounding these in turn are the respective plates 80 and 81. The grids are supported by the respective posts 82 and 83 which are fused into stem 77, and plates 80 and 81 are supported by posts 84 110 and 85, while the ends of the filament are supported by posts 86 and 87. I prefer to provide a base 88 of bakelite which, because of the two additional elements which are present in the tube, is admirably adapted to 115 carry in insulated relation two contact pins 89 and 90 as well as the usual contact pins 91, 92, 93 and 94. Wires which have been shown in dotted lines, carry the connection of the tube elements with the proper contact 120 pins.

I will now set forth the purpose of the unusual shape and arrangement of the tube elements and the manner in which they function. In the functioning of the filaments 125 of radio tubes the material of which the filament is made will throw off electrons as is well known and upon which the operation of a radio tube depends. This electron emission takes place upon and because of the 130

subjection of the filament to the passage of a current sufficient to produce the desired degree of heat necessary to bring about electron activity. Such heat when sufficiently high, will produce an expansion or softening of the material of the filament until its length is too great and permits the material to sag and come into contact with the grid, thus destroying the functioning of the tube. 5 either temporarily or permanently, or perhaps resulting in a short circuiting of the filament with a source of voltage sufficient to burn it out and thus render the tube useless. This is particularly true of tubes having filaments of unusual length. It may also be brought out that in electronic emission from tube elements the direction of emission takes place not only at right angles from the axis of the filament wire, but at various 10 other angles also. For this reason the functioning of the grid and plate of the usual tube permits of the escape or at least the utilization of but a portion of the electrons actually projected from the filament. This 15 is because of the cylindrical shape of the grid and plate, which leaves relatively large openings above as well as below these elements, through which the electrons may escape.

30 In the tubes shown in Figs. 1, 2 and 3 the filaments are spirally shaped so that extreme length is obtained with its advantage of greater electronic emission and concentration within the limitations of the short 35 length of plate and grid encompassing it, but, in this spiral shape it is to be noted that the conical shape of the spiral is of particular merit in that it permits of axial sagging of the convolutions of the spiral instead 40 of sagging sidewise as in the usual filament when elongation or expansion thereof takes place. This avoids the danger of having the filament come into contact with the grid.

The advantage attained in the double 45 ended forms shown in Figs. 1 and 3 is that should the spiral sagging of the filament become too great, thereby tending to too great a concentration of electron activity within a limited region of the entire plate 50 and grid surface, as well as tending to produce a point where the filament and grid might touch, it is merely necessary to remove the tube from its mounting clips and to turn it end for end. This then permits 55 gradual restoration of the sagged filament convolutions to normal conditions and allows them to continue to become sagged toward the opposite end of the tube until it is time to reverse the position of the tube 60 again. This sagging is however of a very limited nature and in fact would never occur except in the event that the filament is subjected to an excessive voltage. The actual tendency however is for the filament convolutions to restore themselves to normal 65

shape and condition each time the filament is allowed to cool, because of the spring-like action of the spiral winding.

In Fig. 3 I have shown the large open ends of the plates and grids as facing each other and spaced apart but slightly. This condition is for the specific purpose of rendering the operation of the tube more efficient than has been heretofore. As I have set forth heretofore, the projection of electrons from a heated filament occurs at all angles therefrom. For this reason the substantial enclosure of the filament by the conically shaped plate and grid elements operates to catch and utilize substantially the entire delivery of electrons from the filament whether such delivery be upward, downward, sidewise or at angles intermediate thereto. Of course this form of the tube is designed to give two tube functioning because of the presence of two grids and two plates, but the same results as far as the relatively complete utilization of projected electrons may be obtained should it be desired to use the tube as a structure having but one 90 filament, one grid and one plate, by merely connecting the two plates together to operate as one and by connecting the two grids together to operate similarly. However it might be of advantage, should it be desired 95 to have such a tube to function as a single tube with filament enclosing grid and plate elements to purposely construct the grid and plate elements in the form of double cone, spherical or other filament enclosing 100 shapes, particularly if the filament is of a shape substantially such as I have set forth.

And now, in Fig. 4 the use of a long filament is shown, but of novel form for use in a single ended tube, but employing multiple grid and plate elements so that the tube may function as more than one ordinary tube. For example, the embodiment shown is that of a tube having two grids and two plates with but one filament having two 110 effective portions, one for each set of grids and plates. Thus, although one long filament is employed, by enclosing each relatively short effective portion of the filament in a closely surrounding grid and a correspondingly close plate substantially as effective efficiency of electron utilization is obtained as with the types shown in Figs. 1 to 3 inclusive. However, in view of the limitation in size of the filament portions 115 and the grid and plate cooperating with each, the individual units of the tube will handle but a portion of the work done by the tubes previously described. Such a tube may be made to handle a much greater volume by connecting the two plates to operate as one and the two grids to operate as one in the same manner. In using the tube so that each unit thereof functions independently, the separate units may be em- 120 125 130

ployed to operate as radio frequency amplifiers or as detectors, while when used jointly as one the tube adapts itself admirably for audio frequency amplification. It might be mentioned that the tubes shown in Figs. 1 to 3 inclusive will function in all three capacities, although for audio frequency amplification the latter is notably successful. The double ended or two unit types shown in Figs. 1 and 3 are remarkably valuable for use in push pull audio amplification circuits, in which the heavy loads impressed upon the two units of the tube will be easily carried because of the large size of the elements, in addition to the fact that the set of elements in each unit is functioning under exactly the same conditions of load, vacuum, filament, voltage and other factors, as the cooperating set of elements, the balancing of these two units being thereby rendered perfect.

In order that my improved form of double ended tubes shown in Figs. 1 and 3 may be properly mounted, I have shown in Figs. 5 to 7 inclusive an improved clip which will permit of a quick, easy, cheap and electrically efficient placing and holding of the tube in position in a set embodying a circuit in which the tube is to be used. This has been described above.

The arrangement of the filaments shown in my improved forms of tube may be likened much to a stream of water through a hose. If the volume of water is great and has to pass through a restricted hose in a given time, it will be projected from the hose in a forceful stream, thus throwing it to a great distance. However, a small volume of water passed through the same hose in the same time may merely drip from the hose in leaving it. So it is with electrons projected from the spiral filaments I have shown. The quantity of electrons projected from such a source will be great and

thus result in a tube possessing powerful amplifying characteristics. If the filament was but a single straight strand, the quantity of electrons would be relatively small and the tube would function correspondingly small.

In Fig. 5, as I have mentioned above, both element units are shown as facing in the same direction. There is an advantage to be obtained by this, because when the filament coils sag they will tend to sag toward the larger end of the tube units and thus prevent any chance of the tube becoming short circuited as well as overcoming the necessity of having to reverse the position of the tube from time to time because of this, as has been explained.

In Fig. 3, as has been explained above, I show the two conical units connected by elements represented by dotted lines. This makes the entire tube function as having but one set of elements. Therefore, it may now be considered that a tube such as I have shown in Fig. 1, could just as readily have two complete dual units of this description as to have the two sets of single units of open ended type which have been shown.

Thus it is that my invention may be capable of many deviations from the exact illustration and description I have given it, without departing from the spirit and scope of the claim which now follows.

I claim:

A radio tube comprising a filament having more than one electron emissive portion, each portion consisting of a cup shaped formation, adjacent portions being separated by non-emissive support portions, and grid and plate elements corresponding in general shape to that of the emissive portions for cooperation therewith.

In testimony whereof I have hereunto affixed my signature.

EUGENE A. KUEN.
